UNITED STATES PATENT OFFICE

SAMUEL E. SPERRY, OF HOLLIS, NEW YORK, ASSIGNOR TO INTERTYPE CORPORATION,
OF BROOKLYN, NEW YORK, A CORPORATION OF NEW YORK

TYPOGRAPHICAL MACHINE

Application filed December 19, 1929. Serial No. 415,291.

The present invention relates to improvements in typographical machines and more especially to those of the general class shown and described in U. S. Letters Patent No. 5 436,532 granted on September 16, 1890 to O. Mergenthaler, wherein matrices bearing character forming faces are delivered from a magazine, by manipulation of a keyboard, and are assembled to form a line from which 10 a type bar or slug is cast. The invention relates more particularly to subsequent improvements of such machines whereby two or more magazines containing different fonts or styles of matrices may be used in the machine and from either of which magazines 15 matrices may be drawn as needed.

Heretofore, it has been the general practice to mount the magazines so that they could be shifted to bring the matrix-releasing 20 escapements of one or another of the different magazines into cooperative relation with relatively fixed escapement actuating means and with a fixed assembler front or chute so that the latter will be in a position to receive 25 matrices delivered thereto from the magazine thus brought into working position, and it has also been proposed to provide a plurality of matrix magazines with escapement actuating mechanism which comprised upper reeds 30 which were arranged in sets individual to the respective magazines and a single set of lower reeds which were shiftable into cooperation with one or another of the upper sets of reeds and were actuated by the keyboard 35 to cause the upper reeds with which they are set to cooperate to actuate the matrix-releasing escapements of the selected magazine; but such mechanisms which have been heretofore proposed have been complicated 40 and expensive in construction and more or less cumbersome or complicated in operation.

The primary object of the present invention is to provide a simplified and improved mechanism for actuating the matrix releasing escapements of one or another of a plurality of magazines and for setting the assembler front to receive the matrices delivered from the selected magazine. The invention is applicable to machines of this 45 general class wherein a plurality of maga-

zines is mounted stationarily in downwardly and forwardly inclined position with their lower forward ends in staggered relation, and it provides escapement actuating reeds and an assembler front, the reeds and assembler front being so mounted and operative that they may be easily and quickly brought selectively into cooperative relation with one or another of the magazines by the operator while occupying his usual position in front of the machine. In the preferred embodiment of the invention a set of upper sections and a set of lower sections are provided, the set of upper sections being mounted for reciprocatory and rotary movement so that they may 55 be swung from cooperative relation with the escapements of one magazine into cooperative relation with the escapements of another magazine, without interference from the lower reed sections, and an upper assembler 60 front section is provided which is movable in properly timed relation with the movements of the upper reed sections so that such upper section of the assembler front will assume cooperative relationship with the selected magazine when the upper reed sections 65 are brought into matrix-releasing relationship with the escapements of that magazine. 70

To these and other ends, the invention 75 consists in certain improvements and combinations and arrangements of parts all as will be hereinafter more fully described, the features of novelty being pointed out particularly in the claims at the end of the specification. 80

In the accompanying drawings:—

Figure 1 is a front elevation of a portion of a typographical machine embodying matrix-releasing mechanism and an assembler front constructed in accordance with 85 the present invention;

Figure 2 is a view of the structure shown in Figure 1 as viewed from the right hand side thereof, the matrix-releasing mechanism being shown set to deliver matrices from the 90 upper one of two magazines and the upper section of the assembler front being shown in position to receive matrices from that magazine; 95

Figure 3 is a view similar to Figure 2 but 100

showing the upper reed sections and the upper section of the assembler front shifted to deliver and receive respectively matrices from the lower magazine, the lower reed sections being ready to shift into position to actuate the upper reed sections;

Figure 4 is a perspective view of the right hand portion of the structure shown in Figure 1; showing the matrix releasing mechanism and the upper section of the assembler front set to release and receive respectively matrices from the upper magazine;

Figure 5 represents a cross section on an enlarged scale taken on the line 5—5 of Figure 3 and looking downwardly;

Figure 6 represents a transverse section on an enlarged scale taken on the lines 6—6 of Figure 3 and looking downwardly; and

Figure 7 is a diagrammatic view of the shifting and locking mechanism, showing the shifting movements of the lower reed sections.

Similar parts are designated by the same reference characters in the several figures.

The present invention is applicable generally to typographical machines of the class embodying a plurality of magazines containing matrices of different styles or belonging to different fonts and in which reciprocating reeds actuated from a keyboard are employed for releasing the matrices from the magazines so that they will be delivered into an assembler front and thence conveyed to a point where the matrices are assembled in a line, preparatory to a casting or similar operation. The invention is particularly applicable to machines of this class in which a plurality of magazines is mounted in a downwardly and forwardly inclined position so that the matrices will travel by gravity to the lower forward ends of the magazines and their delivery is controlled by escapements, the magazines occupying relatively fixed operative positions with their lower forward or matrix delivering ends arranged in staggered relation, that is, the lower matrix delivering end of one magazine is located below and in rear of the lower matrix delivery end of the magazine next above it. The preferred embodiment of the invention is shown in the accompanying drawings and will be hereinafter described in detail, but it is to be understood that the invention is not restricted to the precise construction shown as equivalent constructions are contemplated and such will be included within the scope of the claims.

In the construction shown in the accompanying drawings, 1 represents a portion of the usual face plate casting which is a part of the stationary frame of the machine and is commonly used in machines of this class for mounting the usual assembler front and reed frames, 2 represents a portion of the keyboard frame, a portion of the keyboard 3 being shown in Figure 4, and 4 and 5 repre-

sent matrix containing magazines. The magazines, which may be of the standard construction employed in typographical machines of the general class referred to, may be removably mounted on supports 6 and 7 which are fixed to the stationary main frame of the machine so that while individual magazines may be removed and replaced by other magazines in order to enable different styles or fonts of matrices to be brought into use, the magazines, while in operative position, are relatively stationary with respect to the main frame of the machine and their lower forward matrix delivery ends normally occupy the staggered relation shown in Figures 2 and 3. 8 and 9 represent the escapements which are provided at the lower forward matrix delivery ends of the magazines for controlling the delivery of matrices from the respective magazines. The upper ends of the magazines, according to the arrangement shown, are adapted to receive matrices, after a cast has been made from a line, from a distributing mechanism such for example as that shown in Letters Patent No. 1,202,719 granted Oct. 24, 1916 to T. S. Homans, the distributing mechanism there shown being adapted to return the used matrices to the respective magazines from which they were drawn.

According to the present invention, simplified and improved means is provided for actuating the magazine escapements to effect the delivery of matrices from one or another of the magazines, and cooperative means is provided for receiving the matrices from one or another of the magazines and for directing them to the point of assembly. Preferably, the improved means comprises a set of reeds or keyboard rods which are arranged to be actuated from the usual keyboard, and a set of auxiliary reeds or keyboard rods which are shiftable into working relation with the escapements of one or another of the magazines, these auxiliary reeds being shiftable in a manner which will avoid interference between them and the magazines, especially where the magazines are arranged in staggered relation, and the main keyboard reeds and the auxiliary reeds are relatively shiftable in a manner which will avoid interference between these sets of reeds while the shifting of the auxiliary reeds is taking place; and the assembler front or the means which receives the matrices from the magazines is provided with an upper section which is shiftable into different positions so that it may receive matrices delivered from one or another of the magazines, in accordance with the setting of the escapement actuating reeds. In the preferred embodiment of the invention, means common to the escapement actuating reeds and to the upper shiftable section of the assembler front is provided for concurrently shifting the escapement actu-

ating reeds and the upper section of the assembler front, thereby properly timing and coordinating the shifting of these elements and enabling the shifting of both of these elements to be accomplished by the operation of a single member or part, such as a handle within convenient reach of the operator of the machine while occupying its usual position in front thereof.

In the construction shown in the present instance for carrying out the invention, a set of lower reeds or keyboard rods 10 and a set of upper or auxiliary escapement actuating reeds 11 are employed. The lower reeds 10 are carried by a reed frame 12 which may be similar in its construction to that commonly used in machines of this class, the reeds being individually reciprocable vertically in slotted guides 13 and 14 which engage them near their upper and lower ends but the reed frame 12, according to the present invention, is mounted to rock bodily with the reeds 10 in a forward and rearward direction, the lower end of the reed frame being shown provided in the present instance with knife edges or lugs 15 which rest on the top of the relatively stationary keyboard frame 2 so that they may pivot thereon and allow the upper portion of the reed frame 12 to move in a forward and rear direction with respect to the main frame of the machine. The lower ends of the lower reeds 10 are spaced and arranged directly above the vertically movable ends of the cam operated yokes 16 employed commonly in the keyboards of machines of this class so that the upward movement of any cam yoke will be transmitted to the respective reed or keyboard reed 10 which is directly above it, and by arranging the pivotal center provided by the knife edges 15 in substantial alinement horizontally with the lower ends of the reeds 10, the latter will remain in cooperative relationship with the respective cam yokes of the keyboard, notwithstanding the forward and rearward swinging motion of the reed frame 12. The construction and mode of operation of the keyboard whereby the cam yokes are set into operation from the keys are well understood in this art and illustration and description thereof are deemed unnecessary.

The upper or auxiliary reeds 11 are carried in a frame 17, they being slidably engaged near their upper and lower ends in slotted guide plates 18 and 19 which are fixed to the frame 17 so that these upper reeds are individually reciprocable vertically, and the spacing and arrangement of the upper reeds 11 correspond with the lower reeds 10, and these two sets of reeds are registered so that the upper end of each reed 10 will abut against the lower end of the corresponding upper reed 11. The upper ends of the upper reeds 11, which project above the top guide plate 18, are adapted to cooperate with the

escapements of one or another of the magazines so that when any one of the upper reeds 11 is forced upwardly it will actuate the respective escapement in a direction to cause release of a matrix from the corresponding channel of the respective magazine, it being understood that the spacing of the upper ends of the upper reeds 11 agrees with that of the escapements of the different magazines.

In an arrangement such as that thus far described, the upward movements of the different lower reeds 10 will be transmitted to the upper reeds 11 and the latter will actuate the respective escapements with which these upper reeds are set to cooperate, to effect the release of the matrices from the magazine containing such escapements, but in order to enable a single set of upper reeds 11 to effect the release of matrices from one or another of a plurality of magazines, the set of upper reeds must be shifted out of cooperative relation with the escapements of one magazine and into cooperative relation with the escapements of another magazine, and this shifting movement of the upper reeds must be effected in a manner which will avoid interference between them and the adjacent portions of the magazines, and where the magazines are arranged with their lower matrix delivery ends in staggered relation, as shown in Figures 2 and 3, the upper reeds must be shifted in a path which will avoid interference between their upper ends and the lower end of the magazine which lies between the escapements of that magazine and the escapements of the magazine above it. According to the present invention, the upper reeds 11 are mounted so that their upper ends will rotate or swing in a curved path which will lower them from operative relationship with the escapements of one magazine, then carry them forwardly or rearwardly beneath the lower forward end of an adjacent magazine and then lift these upper reeds into cooperative relation with another magazine, thus avoiding interference between the upper ends of the upper reeds and the intervening magazine structure while shifting from the escapements of one magazine to those of another magazine, and the lower ends of the upper reeds are guided to reciprocate in a substantially vertical path to conform with the rotating or swinging motion of the upper ends of these reeds. In order to avoid interference with the vertical reciprocating movement of the lower ends of the upper reeds from the lower reeds 10 which are normally directly below them, the upper ends of the lower reeds are swung out of the path of the upper reeds and preferably into a position off-set rearwardly therefrom, the lower reeds being returned to their normal working relationship with the lower ends of the upper reeds after the latter have been

shifted into one or another of their different operative positions.

In order to effect the above described shifting movements of the upper reeds 11, the upper end of the frame 17 carrying these reeds is pivotally connected at its opposite sides and by the pivot pins 20 to a pair of cranks 21 which are fixed to and extend at the same angle from a shaft 22, the latter 10 extending transversely of the machine and being mounted to rotate in brackets 23 which are bolted or otherwise secured to the top of the stationary frame member 1, the cranks 21 being of such a length that they will swing the upper ends of the upper reeds 11 in an 15 arc or path which will carry them from the escapements 8 of the upper magazine into cooperation with the escapements 9 of the lower magazines, or vice versa, when the shaft 22 to which the cranks 21 are fixed, is rotated through a sufficient angle, and the arc or path through which the upper ends 20 of the reeds 11 are thus swung will enable the upper ends of the reeds 11 to pass the lower forward corner of the lower magazine 5 without striking it. The lower end of the frame 17 carrying the upper reeds 11 is guided for vertical reciprocatory motion by pivot pins 24 which project laterally 25 from its opposite sides and operate vertically in slots 25 formed in brackets 26, the latter being bolted or otherwise fixed to the stationary frame 1. The lower end of the upper reed carrying frame 17 is thus enabled to rise 30 and fall in conformity with the swing of the upper end of said frame in an arcuate or curved path and to pivot incidentally to such motion of the upper end of the frame 17.

In order to permit descent of the upper reed carrying frame 17 incident to the shifting thereof to carry the upper reeds out of operative relation with the escapements of one magazine and to bring them into cooperation with the escapements of another magazine, the lower set of reeds 10 must be removed from the path of descent of the upper set of reeds, and this is accomplished in the present instance by swinging the lower reed carrying frame 12 rearwardly before the upper reed carrying frame 17 descends, so that the lower end of the upper reed carrying frame 17 will not be obstructed by the lower reed carrying frame 13. In the preferred construction, means is provided for coordinating and properly timing the shifting movements of the lower and upper reed carrying frames. The means shown in the present instance for accomplishing this result comprises a shaft 27 which is mounted to rotate in a suitable bracket 28 which may be bolted or otherwise fixed to the stationary frame 1, this shaft having a handle 29 fixed thereon, the handle being located on the machine near and above the keyboard so that the operator while occupying his usual po-

sition in front of the machine may manipulate this handle to shift the escapement actuating mechanism to effect delivery of matrices from one or another of the magazines, as described. The shaft 27 has a cam 30 fixed thereon and arranged to bear on a slide or projection 31 which bears at its rear end against the front of the lower reed frame 12, the slide 31 being guided to reciprocate in a forward and rearward direction in the bracket 26, the cam 30 being so shaped that when the handle 29 is in one position, as for example its raised position shown in Figure 2, the lower reed carrying frame 12 will occupy its normal forward position and when the crank 29 is swung downwardly from that position, the lower reed carrying frame 12 will be shifted into a rearwardly off-set position out of the path of movement of the lower end of the upper reed carrying frame 17, as for example, is shown by the full lines in Figure 3. The lower reed carrying frame 12 is maintained in operative relation with the rear end of the slide 31 and the forward edge of the latter is maintained in contact with the periphery of the cam 30 by a tension spring 32 which is stretched between the lower reed carrying frame 12 and the stationary bracket 28. The shaft 22 which serves to shift the upper reed carrying frame 17 is connected in the present instance to the shaft 27 by sprocket wheels 33 and 34 on these shafts and a connecting sprocket chain 35. Means is provided for locking the upper reed carrying frame 17 against shifting movement until after the lower reed carrying frame 12 has been shifted out of its normal operative position so that it will clear the upper reed carrying frame when shifted. For this purpose, the sprocket wheel 33 is fixed to the shaft 22 but the sprocket wheel 34 is mounted loosely on the shaft 27 and is fixed to a locking disk 36 which is also mounted loosely on the shaft 27, the sprocket wheel 34 and locking plate 36 being capable of a limited rotation on the shaft 27 and being adapted to be connected to said shaft by a pin or projection 37 which projects radially from the shaft 27 into a segmental slot or recess 38 formed in for example the hub of the sprocket wheel 34. The locking plate 36 which is fixed to the sprocket wheel 34 serves to lock and thus retain the shifting means for the upper reed sections in either of its two operative positions. For this purpose, the locking disk is provided with locking recesses 36^a and 36^b which extend inwardly from its periphery and are suitably spaced circumferentially thereof, and the forward end of the slide 31 is formed with a tooth 31^a which is shaped to fit into one or the other of said recesses in the locking disk. The cam 30 has a portion of its peripheral surface raised to an extent sufficient to cause the tooth 31^a to be completely disengaged from the locking disk while this raised

- portion of the cam is in engagement with the cooperating forward edge 31^b of the slide 31, the remainder of the circumference of the cam 30 being depressed sufficiently to permit complete engagement of the tooth 31^a in one or another of the notches 36^a, 36^b when such depressed portion of the cam is opposite to the forward edge 31^b of the slide. Inclines 30^a and 30^b connect the relatively raised and depressed portions of the cam and provide inclines on which the cooperating edge 31^b of the slide rides. Undue movement or displacement of the slide 31 from its guide or bearing in the bracket 26 is prevented by a screw 39 which is fitted into the bearing for the slide and has its inner end arranged to project into a longitudinal slot 40 of suitable length formed in the slide, this screw allowing the slide to reciprocate through its full range of the movement under the action of the cam 30 but preventing displacement of the slide from its bearing.

5
10
15
20

the inclined surface 30^a on the cam is thus acting on the slide, the locking disk 36 remains motionless or substantially so, as the tooth 31^a on the slide is still engaged in the notch 36^a of the locking disk, although it is being withdrawn from said notch by the receding movement of the slide 31, and since the sprocket wheel 34 which serves to rotate the shaft 22 which shifts the upper reed frame 17 is fixed to the locking plate 36, shifting of the upper reed frame will be delayed during the initial part of the swing of the crank or handle 29. The handle 29 is permitted to swing and thus rotate the cam 30 while the locking disk 36 remains motionless, by the lost motion provided between the locking disk 36 and the pin 37 by the segmental slot 38 in which said pin operates, the pin 37 moving idly in the segmental slot 38 during that part of the rotation of the shaft 27 which causes the forward edge 31^b on the slide 31 to ride

70
75
80
85
90

When the upper and lower sets of reeds are in operative relationship and set to actuate the escapements 8 of the upper magazine, as shown in Figure 2, the forward edge 31^b of the slide 31 is opposite to the relatively low portion of the cam 30 and the tooth 31^a on the slide is fully seated in the recess 36^a of the locking disk, the lower reed frame 12 being then in its normal forward position so that the upper ends of the lower reeds are in position to engage the lower ends of the upper reeds to actuate them. Since the shaft 22 which shifts the upper reed frame 17 is connected by the sprocket wheels 33 and 34 and the sprocket chain 35 to the locking disk 36 so that the shaft 22 can rotate only when the locking disk rotates, it will be understood that while the tooth 31^a remains engaged in the notch 36^a of the locking disk, the upper reed frame will be locked in a position where the upper ends of the upper reeds 11 cooperate with the escapements 8 of the upper magazine 4, as shown in Fig. 2, and displacement of the upper reed frame will be prevented. While the escapement actuating mechanism is set for operation upon the escapement of the upper magazine, the operating handle 29 may occupy a raised position substantially as shown in Fig. 2. Resetting of the escapement mechanism to bring it into operative relationship with the escapements 9 of the lower magazine 5 is effected simply by a downward swing of the crank or handle 29 through approximately a half revolution. During the first operation of the downward swing of the crank or handle 29, the cam 30, which is fixed to the shaft 27 and hence rotates in unison therewith, will act, through its inclined surface 30^a engaging the surface 31^b of the slide 31 to push this slide, and the upper portion of the lower reed frame 12 against which it bears, rearwardly. While up the inclined surface 30^a of the cam. The slot 38 is of sufficient length to permit the pin 37 to advance while the locking disk 36 remains stationary or substantially so, until the incline 30^a on the cam has passed the edge 31^b of the slide, at which time the tooth 31^a will have been completely withdrawn from the locking notch 36^a in the cam. When the shaft 37 and the cam fixed thereon have rotated to that extent, the pin 37 fixed on the shaft 27 will reach the end of the segmental recess 38 and it will then couple the sprocket 34 and the locking disk 36 to shaft 27 so that these elements will rotate in unison with said shaft during its further rotation, and as the withdrawal of the tooth 31^a from the notch 36^a in the locking plate unlocks the sprocket 34, the latter will be free to rotate in unison with the shaft 27 and the motion communicated from this sprocket through the chain 35 to the sprocket wheel 33 fixed on the shaft 22 will rotate the latter in an anti-clockwise direction in Figure 2 and the cranks 21 fixed on this shaft will swing the upper reed carrying frame 17 through an arcuate or curved path which will lower the upper ends of the upper reeds 11 then swing the same rearwardly beneath the forward end of the lower magazine 5 and will finally raise the upper ends of the upper reeds until they assume the position shown in Figure 3 where they are in cooperative relation with the reeds 9 of the lower magazine 5.

During the above-described shifting movement of the upper reed frame 17, the lower reed frame 12 is in a rearwardly shifted or off-set position, this lower reed frame being shifted into such a position by the rearward movement imparted to the slide 31 by the cam 30. Figure 3 shows in dotted lines the position of the upper reed frame 17 while it is at an intermediate point in its shifting

movement, the lower end of the upper reed frame being then below the upper end of the lower reed frame 17, but as the latter is then in its rearwardly shifted position the lower reed frame will avoid interference with the shift of the upper reed frame. When the crank or handle 29 has been rotated to an extent sufficient to bring the upper reed frame 17 into cooperation with the lower magazine, 10 as shown by the full lines in Figure 3, the second inclined surface 30^b on the cam 30 will have reached the cooperating edge 31^b of the slide 31, and as the swinging motion of the handle 29 continues, the edge 31^b of the slide 15 will ride down the inclined surface 30^b on the cam and the tooth 31^a on the slide will enter the second notch 36^b in the locking plate, under the tension of the spring 32 which acts 20 constantly and yieldingly to swing the lower reed frame 12 forwardly, and the final movement of the crank or handle 29 will cause the tooth 31^a to become fully seated in the notch 36^b and will cause the slide 31 to assume its foremost position, the engagement of the 25 tooth 31^a in the notch 36^b of the locking disk locking the shaft 22 against rotation so that shifting of the upper reed frame 17 out of cooperative relation with the escapements of the lower magazine is prevented, and the 30 lower reed frame 17 will occupy its forward operative position so that the upper ends of the lower reeds 10 register with the lower ends of the upper reeds 11, and upward movements imparted to the lower reeds 10 by manipulation of the keyboard in the usual way 35 in the selection of matrices will be transmitted to the upper reeds 11, and as the latter then cooperate with the escapements 9 of the lower magazine 5, the respective escapements 40 in this magazine will be actuated to effect the release of matrices from the lower magazine.

In order to reset the escapement actuating mechanism for operation upon the escapements 9 of the upper magazine 4, it is only 45 necessary to swing the crank or handle 29 upwardly until it reaches the position shown in Figure 2. During the initial part of the upward swing of the handle 29, shifting movement of the upper reed frame 17 will be prevented as the tooth 31^a of the slide 31 is engaged in the notch 36^b of the locking disk and the latter with the sprocket 34 are thus locked against rotation, but the initial part 50 of the upward swing of the handle 29 will cause the inclined surface 30^b on the cam 30 to act on the slide 31 to force it rearwardly, thereby moving the lower reed frame 12 into the rearwardly off-set position shown by the full lines in Figure 3, and during this movement of the lower reed frame, due to the rearward movement of the slide 31, the tooth 31^a 55 on the slide is being withdrawn from the notch 36^b in the locking disk. Rotation of the shaft 27 and handle 29 during this part of the 60 operation without interference from the lock-

ing disk 36 is permitted by the segmental notch 38 in which the pin 37 operates, the pin 37 moving idly in the recess 38 during this initial part of the shifting operation, but when the tooth 31^a has been fully retracted 70 from the notch 36^b in the locking disk, the pin 37 reaches the end of the recess 38, and continued rotation of the shaft 24 incident to the upward swing of the handle 29 will cause the locking disk and the sprocket 34 fixed to it to rotate in unison with the shaft 27 and the shaft 22 will then be rotated in a clockwise direction, the cranks 21 fixed thereon acting to swing the upper reed frame 17 in an arcuate or curved path which will carry the upper ends of the upper reeds first in a downward direction which lowers them out of cooperative relation with the escapements 9 of the lower magazine 5, thence in a forward direction which carries them beneath the 80 lower forward end of the lower magazine and then in an upward direction which brings the upper ends of the upper reeds into cooperative relation with the escapements 8 of the upper magazine 4, as shown in Fig. 2. 90 During this shifting movement of the upper reed frame, the lower end of this upper reed frame reciprocates vertically, as will be apparent from the full and dotted line illustration of the upper reed frame 17 in Figure 3, but these movements of the lower end of the upper reed frame are not interfered with by the lower reed frame 12 as the latter occupies its rearwardly off-set position, as shown by the full lines in Figure 3 during such shifting movements of the upper reed frame. The final portion of the upward swing of the crank or handle 29 brings the inclined surface 30^a of the cam 30 into engagement with the surface 31^b of the slide 31 and as the inclined surface 30^a passes the edge 31^b of the slide the latter moves forwardly under the tension of the spring 32 acting on the lower reed frame 12, and the lower reed frame is thus caused to move forwardly toward and into its normal operative position where the upper ends of the reeds 10 register with the lower ends of the upper reeds 11, and this forward movement of the slide 31 engages the tooth 31^a on the slide in the notch 36^a in the locking disk so that when the shifting movement has been completed the shaft 22 which shifts the upper reed frame will be locked against rotation and the upper reeds will be thus held in cooperative relationship with the 100 escapements of the upper magazine. 110

The present invention also provides simple and improved means to receive the matrices delivered from one or the other of the magazines and to direct them to the assembling means, such receiving means being preferably coupled to the escapement shifting mechanism whereby the matrix receiving means will be shifted in proper timed relation to the shifting of the escapement actuating mech- 115 120 125 130 135

anism. As shown in the present instance, 40 represents the conveyer belt as commonly used in typographical means for conveying the matrices through the assembler front 41 to the usual assembling elevator or other point of assembly, and according to the present invention, the assembler front is provided with an upper section 42 the lower end of which remains in position to deliver matrices 5 to the lower portion of the assembler front but the upper portion of which is shiftable so as to bring it into position to receive matrices which are released from the upper or the lower magazine. As shown, the upper 10 section of the assembler front has its lower end pivoted at 43 to a suitable bracket on the stationary part of the frame 1, this assembler front section being formed with the usual matrix guiding partitions, and this section of 15 the assembler front is of such height that when it is in one position it will extend between the remainder or lower portion of the assembler front and the lower forward matrix delivery end of the upper magazine, 20 as shown in Figure 2. In order to enable this upper shiftable section of the assembler front to receive matrices delivered from the lower rearwardly positioned magazine 5, a bridge piece 44, which has partitions therein spaced 25 in alinement with the partitions of the assembler front section 42, is mounted in fixed position opposite to the lower forward end of the lower magazine 5 so that it forms in effect 30 a continuation of this lower magazine, this bridge piece extending downwardly sufficiently to join the upper end of the assembler front section 42 when the latter is swung 35 into a position to receive matrices from the lower magazine 5, as shown in Figure 3. The bridge piece is mounted in fixed position on the brackets 23 mounted on the frame 1, and it will be seen upon comparison of Figures 2 40 and 3 that the upper ends of the upper reeds 11, during their shifting movements, will 45 swing through a path which will clear the bridge piece.

The upper section of the assembler front is shifted in proper timed relation with the shifting of the upper reed sections preferably 50 by the shaft 22 which effects the shifting movements of the upper reed sections, the shaft 22 being provided for this purpose with cranks 45 which are fixed thereon toward its opposite ends and extend at the same angle 55 therefrom, and the crank pins 46 of these cranks are pivotally connected to links 47 which are pivotally connected at 48 to the respective sides of the assembler front section 42. The cranks 45 are of such length and 60 located at such an angle with respect to the cranks 21 on the shaft 22 that they, together with the links 47, will position the upper assembler front section 42 to receive matrices released from the upper magazine 4 when the upper reed frame 17 is positioned to cause

the upper reeds 11 to actuate the escapements of the upper magazine, as shown in Figure 2, and to aline the assembler front section 42 with the bridge piece 44 and the lower magazine 5 when the upper reed frame 17 is shifted 70 to bring the upper reeds into working relation with the escapements of the lower magazine, as shown by the full lines in Figure 3. It will be understood that the cranks 45 which are fixed on the shaft 22 and swing in unison with the cranks 21 fixed on said shaft, will cause the assembler front section 42 to swing concurrently from working relation with one magazine into working relation with the other magazine while the escapement actuating mechanism is being correspondingly shifted, the shifting of the upper assembler front section 42 as well as the shifting of the escapement actuating mechanism being effected by the operation of the crank or handle 29 as has been hereinbefore described.

The radius of the arc through which the upper ends of the upper reed sections swing is substantially shorter than the length of these upper reed sections, and preferably, the center of this arc is located immediately below the lower forward end of the lower magazine, so that the upper ends of the upper reed sections, in swinging out of cooperative relation with the escapements of one magazine 5 and into cooperative relation with those of the other magazine, will travel in an arc which is substantially greater than a half circle, and the lower forward end of the lower magazine will be located above and substantially opposite to the lowest part of the arc while the escapements of the different magazines will be located at the ends of the arc which are above the center of the arc, this relative disposition of the center of the arc, the angle included by it and the location of its termini enabling the upper ends of the upper reed sections to clear the lower forward end of the lower magazine and the bridge piece or extension thereof during the shifting of the upper reed sections from the escapements of one magazine to those of the other magazine.

The mode of operation of the escapement actuating mechanism and shiftable assembler front section as hereinbefore described is briefly as follows. When the upper magazine 4 is in use, the handle or crank 29 occupies its upper position as shown in Figure 2, the slide 31 then occupying its foremost position as its forward edge 31^a is then opposite to the low portion of the cam 30, and the lower reed frame 12 will occupy its normal forward position as shown in Figure 2. Also, the tooth 31^b on the slide 31 will be 125 fully seated in the notch 36^a of the locking disk 36, thereby locking the disk 36 and the sprocket wheel 34 fixed to it, against rotation. At this time, the cranks 21 on the shaft 22 will occupy their forward upwardly in-

clined position so that the upper reed frame 17 will be in its forward elevated position, the lower ends of the upper reeds 11 being then immediately above and in alignment 5 with the lower reeds 10 so that reciprocations of the latter will be transmitted to the upper reed sections, and the upper ends of the upper reed sections 11 will be registered and in working relation with the escapements 8 of 10 the upper magazine, so that operation of the usual keyboard which serves to lift and thus actuate the lower reed sections 10 will be transmitted through the upper reed sections 11 to the escapements of the upper magazine 15 4 and matrices stored in this magazine will be released therefrom, as desired by the operator.

While the cranks 21 which shift the upper reed frame 17 occupy the angular position 20 described, the cranks 45 which operate upon the links 47 to shift the upper assembler front section 42 will also occupy the forwardly and upwardly inclined positions shown in Figure 2, and in consequence, the upper assembler front section 42 will be positioned by the cranks 45 and links 47 to receive the matrices delivered from the upper magazine and to conduct them to the lower section 25 of the assembler front for conveyance by the usual travelling belt 40 to the point where the matrices are assembled in a line. The spring 32 acts to maintain the lower reed frame 12 in its forward operative position so that the lower reed sections contained therein 30 will maintain proper cooperative relationship with the upper reed sections, and the engagement of the tooth 31^a of the slide 31 in the notch 36^a of the locking disk will lock the shaft 22 against rotation, so that 35 the upper reed frame 17 is locked in position where the upper ends of the upper reeds are in cooperative relation with the escapements of the upper magazine.

In order to shift the escapement mechanism and the upper section of the assembler front for the release and delivery of matrices from the lower magazine, it is only necessary for the operator to grasp the handle or crank 29 and to swing it downwardly. During the 40 initial part of the downward swing of the handle 29, the upper reed frame 17 and the upper shiftable section of the assembler front remain stationary, as the tooth 31^a engaging in the notch 36^a of the locking disk locks the shaft 22 against rotation, but the cam 30 begins to rotate immediately and its inclined surface 30^a engages the forward edge 31^b of the slide 31 whereby the latter is shifted 45 rearwardly, and as this slide bears against the forward side of the lower reed frame 12, the latter also will be rocked or tilted rearwardly against the action of the spring 32, and this rearward shift of the slide 31 will continue until the upper end of the lower reed frame 12 has been removed rearwardly 50

from beneath the lower end of the upper reed frame 17. When this stage in the operation has been reached, the tooth 31^a on the slide 31 is fully retracted from the notch 36^a in the locking disk 36 and the projection 37 which is fixed to the shaft 27 and which has been 55 previously moving idly in the segmental slot 38 in the hub of the sprocket wheel 34, reaches the end of said segmental slot so that continued rotation of the shaft 27 under the action of the handle 29 will cause the sprocket wheel 34 and the locking disk 36 to begin to rotate in unison with the shaft 27. Such rotation of the sprocket wheel 34 is transmitted, 60 through the chain 35 to the sprocket wheel 33 fixed on the shaft 22, so that the latter then begins to revolve, and this rotation of the shaft 22 causes the cranks 21 fixed thereon to swing the upper end of the upper reed frame 17 in an arc the direction of which is first downward whereby the upper reed sections 11 are lowered, thence rearwardly whereby the upper ends of the upper reed sections are carried beneath the bridge piece or extension 44 at the lower forward end of the lower magazine 5, substantially as is indicated by the dotted lines shown in Figure 3 and thence upwardly whereby the upper ends of the upper reed sections 11 are raised into cooperative relation with the escapements 9 of the lower magazine 5, as shown by the full lines in Figure 3. While the upper end of the upper reed frame 17 is thus swinging in an arcuate path, the lower end of this reed frame reciprocates vertically, it being guided in its reciprocating motions by the pivot pins 24 and the guide slots 25, and although the lower end of the upper reed frame 17, during these reciprocating movements, will descend below the top of the lower reed frame 12, there will be no interference between the reed frames as the upper end of the lower reed frame is then shifted rearwardly where it is off-set 65 from the path of the lower end of the upper reed frame. The cranks 45 which swing in unison with the cranks 21 during rotation of the shaft 22 will act, during the shifting movement of the upper reed frame just described, to swing the upper assembler front 70 42 from the operative position shown in Figure 2, through the intermediate position shown by the dotted lines in Figure 3 and into the full line position shown in Figure 3 where it will align or register with the bridge piece or extension 44 at the lower forward end of the lower magazine 5 so that this shiftable section of the assembler front will be thus brought into position to receive 75 matrices delivered from the lower magazine and to direct them into the lower portion of the assembler front.

As the cam 30 and locking disk approach those positions in their rotation where the upper reed sections 11 are brought into cooperative relation with the escapements of 80 130

the lower magazine 5, the inclined surfaces 30^b on the cam reaches the forward edge 31^b of the slide 31 and the latter is permitted to return to its forward position. During this 5 forward movement of the slide 31, the lower reed frame 12 swings back toward and finally into its normal forward position and the tooth 31^a on the slide moves into the second notch 36^b in the locking disk which notch is 10 then registered with the tooth, and the tooth 31^a becomes fully seated in the notch 36^b at the moment the shaft 22 has rotated to the point where the upper ends of the upper reed sections 11 have been brought fully into co- 15 operative relation with the escapements of the lower magazine, and at this moment the crank or handle 29 is locked against further rotation and the escapement mechanism and also the shiftable upper assembler mecha- 20 nism are locked in working relation with the lower magazine.

In order to shift the escapement actuating mechanism and the upper section of the assembler from cooperative relation with the 25 lower magazine into cooperative relation with the upper magazine, it is only necessary to swing the crank or handle 29 upwardly or back to the full line position shown in Figure 2. During the first part of this move- 30 ment of the handle 29, the pin 37 fixed in the shaft 27 moves idly toward the opposite end of the segmental slot 38 in the hub of the sprocket wheel 34 so that the latter and the locking disk 36 will remain motionless and 35 then will be locked by the engagement of the tooth 31^a in the notch 36^b, so that premature shifting of the upper reed frame will not take place, but the cam 30 which begins to rotate concurrently with that of the shaft 27 40 will act, through the operation of the inclined surface 30^b thereon, upon the slide 31 to push it rearwardly, thereby shifting the lower reed frame 12 out of its normal forward position toward its rearwardly off-set position and to 45 disengage the tooth 31 on the slide from the notch in the locking disk, and after the lower reed frame 12 has been fully shifted to the rear and the tooth 31^a on the slide 31 has been 50 fully disengaged from the notch 36^b in the locking disk 36, the pin 37 fixed to the shaft 27 will have reached the end of the segmental slot 38 and will cause the sprocket wheel 34 and locking disk to rotate in unison with the 55 rotation of the shaft 27, thereby causing the shaft 22 to rotate in a direction which is the reverse of that previously described whereby the upper reed sections are first lowered out of cooperative relation with the escapements of the lower magazine 5 then swung forward- 60 ly beneath the lower forward end of the lower magazine, and the bridge piece or extension 44, and finally upwardly whereby the upper ends of the upper reed sections are raised into cooperative relation with the es- 65 capement of the upper magazine 4, as shown

in the full lines in Figure 2, and during this shifting operation of the upper reed frame 17, the upper section 42 of the assembler front is shifted from the full line position shown in Figure 3 through the dotted line position shown in that figure, and finally into the full line position shown in Figure 2. During the final part of the shifting movements of the upper reed frame and the upper section of the assembler front, the cam 30 allows the slide 31 to return to its normal forward position, the lower reed frame 12 being thereby returned to a position beneath the lower end of the upper reed frame so that the reeds carried by the lower reed frame will register and 70 cooperate with those carried by the upper reed frame, and the tooth 31^a on the slide enters the notch 36^a in the locking disk, it finally seating therein and thereby arresting the crank or handle 29 when it reaches the po- 75 sition shown in Figure 2, the shaft 22 which shifts the upper reed frame and the upper section of the assembler front being then 80 locked so that displacement of the upper reed frame or the upper section of the assembler front from operative position is prevented. 85

I claim as my invention:—

1. In a typographical machine embodying a plurality of matrix magazines having matrix releasing escapements, actuating reeds shiftable at their upper ends in an arcuate path the center of which is above said path and below the height of the escapements and the radius of which is shorter than the length of said reeds, to bring said ends of the reeds into cooperative relation with the escapements of one or another of the magazines. 95

2. In a typographical machine embodying a pair of superposed matrix magazines arranged in a downwardly and forwardly inclined position with their lower forward ends in staggered relation and having matrix releasing escapements, actuating reeds shiftable at their upper ends in an arc of more than a half circle about and beneath a center located immediately below the lower forward end of the lower magazine to bring said ends of the reeds into cooperative relation with the escapements of one or another of the magazines. 105

3. In a typographical machine embodying a plurality of matrix magazines having matrix releasing escapements, escapement actuating reeds the upper ends of which are shiftable in a curved path about and beneath a center located below the height of the escapements to carry them into cooperative relation with the escapements of one or another of the magazines and the lower ends of which are reciprocable in a fixed vertical plane in conformity with said movement of their upper ends. 115

4. In a typographical machine embodying a plurality of matrix magazines having matrix releasing escapements, upper and lower 120

- escapement actuating reeds, the upper reeds being mounted to swing so that their upper ends travel in a curved path having a center which is above said path and below the height of the escapements of the magazines and having a radius which is shorter than the length of said upper reeds to carry their upper ends to and from cooperative relation with the escapements of the different magazines while their lower ends are guided to reciprocate in a fixed vertical plane, and the upper ends of the lower reeds being movable to and from operative position in said fixed vertical plane beneath the upper reeds.
- 15 5. In a typographical machine embodying a plurality of matrix magazines having matrix releasing escapements, a frame carrying escapement actuating reeds, a shaft having crank means thereon supporting the upper end of the reed frame to swing into positions at opposite sides of said shaft and operable, when rotated, to swing the upper ends of the reeds from cooperative relation with the escapements of one magazine into cooperative relation with the escapements of another magazine, and means guiding the lower end of the reed frame to move in a fixed vertical plane during said swinging movement of its upper end.
- 20 6. In a typographical machine embodying a plurality of matrix magazines having matrix releasing escapements, a set of escapement engaging reeds mounted to shift at their upper ends in an arc which will carry them into cooperative relation with the escapements of one or another of the magazines and to reciprocate longitudinally at their opposite ends, a set of keyboard-actuated reeds mounted to shift to and from operative position opposite to the longitudinally reciprocable ends of the escapement engaging reeds, operating means for being operative, by its movement in one direction, to shift both sets of reeds, said means shifting the keyboard-actuated reeds out of operative position and to then shift the escapement engaging reeds and comprising means for locking the escapement engaging reeds against shifting until such shifting of the keyboard-actuated reeds has been completed.
- 25 7. In a typographical machine embodying a plurality of matrix magazines and having matrix releasing escapements, a set of escapement engaging reeds shiftable at their upper ends into cooperative relation with the escapements of one or another magazine and reciprocable longitudinally at their opposite ends, a set of key-board actuated reeds shiftable to and from cooperative relation with the reciprocatory ends of the escapement engaging reeds, and means operative by its movement in one direction to shift both sets of reeds and comprising means controlled by said movement for locking the escapement
- 30 15 engaging reeds against shifting until after

the shifting of the keyboard-actuated reeds out of operative position has been completed and for locking the escapement engaging reeds against shifting after the shifting thereof and the return of the keyboard-actuated reeds have been completed. 70

8. In a typographical machine the combination of sets of upper and lower individually shiftable escapement actuating reeds, and common operating means therefor embodying a rotatable shaft having a cam thereon, a member cooperative with the cam to shift the lower reeds, means operative by the shaft to shift the upper reeds, and locking means controlled by said cam for preventing shifting of the upper reeds until shifting of the lower reeds has been completed. 80

9. In a typographical machine, the combination of sets of upper and lower escapement actuating reeds, the upper set being shiftable to bring them into cooperative relation with the escapements of one or another of a plurality of magazines and the lower set of reeds being shiftable into and out of cooperative relation with the upper reeds, means for shifting both sets of reeds in definite timed relationship including a shaft having a cam fixed thereon, a member cooperative with the cam and operative thereby to shift the lower set of reeds, an element relatively rotatable to a limited degree on the shaft for shifting the upper set of reeds, a locking member connected to said element, and means controlled by said cam and cooperative with said locking member to prevent shifting of the upper set of reeds while the lower set of reeds are in cooperative relation therewith and operative by said cam to release said locking member when shifting of the lower set of reeds has been completed. 90

10. In a typographical machine embodying a plurality of matrix magazines having matrix releasing escapements, the combination of escapement actuating reeds, means including a shaft and crank means thereon for supporting the reeds to swing, at their upper ends, in an arc the radius of which is shorter than the reeds and the center of which is above the arc and below the height of the escapements of the magazines to carry the upper ends of the reeds from cooperative relation with the escapements of one magazine into cooperative relation with the escapements of another magazine, an assembler front section mounted to swing in an arc about a center off-set forwardly from the center of the arc in which the reeds swing and crank means on said shaft connected to the assembler front section and operative by said shaft to swing the assembler front section into matrix-receiving position with respect to one or another of the magazines. 110

In testimony whereof I have hereunto set my hand.

SAMUEL E. SPERRY. 130
